UNITED STATES PATENT OFFICE.

MAX HERSKOVITZ, OF CHICAGO, ILLINOIS.

ELECTRIC-LIGHTING FIXTURE.

1,395,710.

Specification of Letters Patent.

Patented Nov. 1, 1921.

Application filed October 18, 1918. Serial No. 258,721.

To all whom it may concern:

Be it known that I, MAX HERSKOVITZ, a citizen of the United States, and a resident of Chicago, Cook county, and State of Illinois, have invented certain new and useful Improvements in Electric-Lighting Fixtures, of which the following is declared to be a full, clear, and exact description.

This invention relates to electric lighting fixtures, and its primary object is to provide a fixture that may be quickly and readily assembled, wired and attached to a ceiling, wall or other support. Another object is to provide an electric lighting fixture with a receptacle, as a part of the fixture itself, of improved construction for removably holding any of the usual and well known standard electric sockets, snap switches, pull switches, plugs, insulators and the like. The standard commercial sockets, switches, and so forth, used in electric lighting fixtures, are universally provided with a casing or cover constructed of brass, fiber or porcelain, but the interior was not ordinarily used to put into a fixture without its casing. The brass casing is an expensive portion of the switch, and one of the objects of this invention is to provide an electric lighting fixture with an integrally formed receptacle, wherein the interior of standard commercial sockets, switches and the like, may be held in the fixture. In other words, I dispense with the use of the casing of electric sockets, switches and so forth in the present fixture, thereby saving a large proportion of the cost of the switch and considerable labor. Moreover, the invention provides for a form of fixture that may be accommodated to various types of fixtures, such as pendant stem, wall bracket fixtures and ceiling fixtures.

One of the particular advantages of my invention is, that it does away with the usual insulating joints which must be used in almost all electric lighting fixtures when installing them. This is because I can use heavy insulated wire at the extreme end of the fixture.

The invention consists in the several novel features hereinafter fully set forth and claimed.

The invention is clearly illustrated in the accompanying drawings, in which:

Figure 1, is a side elevation of a pendant stem electric lighting fixture, embodying a simple form of the present invention; Fig.

2, is a side elevation of an embodiment of the invention in the form of a wall bracket fixture; Fig. 3, is a side elevation of an embodiment of the invention in the form of a ceiling fixture; Fig. 4, is a detail, central vertical section of the switch containing members of the fixture shown in Fig. 1, a chain pull switch being shown therein partly broken away, the line of section is taken at 4-4 in Fig. 5; Fig. 5, is a detail horizontal section taken on line 5-5 in Fig. 4; Fig. 6, is a detail, central, vertical section taken on line 6-6 in Fig. 5; Fig. 7, is a side elevation of a fragment of the combined stem and receptacle, and Fig. 8, is a detail, central vertical section of the combined locking device and shade holder, the line of section being taken at 8-8 in Fig. 5.

Referring to said drawings and first to Figs. 1 and 4 to 8 inclusive, the reference character 15 designates a pendant tubular stem, which has a screw threaded end portion 16, adapted to be attached to a suitable supporting member which is secured to the ceiling. Below its end portion 16, the stem 15 is formed with an outlet opening 16^a for the conductor cords. A canopy 17, surrounds the upper portion of the stem 15, and encloses the supporting and connecting members and wires as usual.

The lower end of the stem 15, is enlarged to provide a receptacle 18, for holding the interior of an electric socket 19, here shown as of the chain pull type. For convenience, the stem and receptacle will be termed the combined stem and receptacle, and detachably secured thereto is a lower shade holding and locking member 24, which for convenience, may be termed a combined shade holder and locking device. Said combined shade holder and locking device hugs the socket and locks the same in place in the receptacle, making it secure therein. The means here shown for detachably connecting said combined stem and receptacle, and combined shade holder and locking device comprises lugs 25, on the combined stem and receptacle, and bayonet slots 26, formed on the internal face of the combined shade holder and locking device. The bayonet slots open up through the upper edge of the combined shade holder and locking device and have end portions 27, extending at right angles to the other portions of the slots. It will be understood that by insert-

100
105
110

ing the lugs 25, into the bayonet slots and turning one member upon the other, the lugs will be brought into the portions 27, of the slots thereby connecting the two members together. The combined stem and receptacle has an annular flange 28, against which the upper edge of the combined shade holder and locking device is firmly held by the lugs and bayonet slot connections. A 10 set screw 29, is screwed in the combined shade holder and locking device, and its protruding end lies in front of an edge 30^a, of a notch 30, in the combined stem and receptacle and positively prevents relative rotation between the combined stem and receptacle and combined shade holder and locking device. The screw 29, also bears against the body portion of the socket and steadies it. The arm 21, of the socket projects out 15 through the notch 30.

In the form of combined stem and receptacle illustrated the combined shade holder and locking device 24, is formed with a shade holder which may comprise a flaring 25 or skirt portion 31, in which are threaded screws 32, said screws acting to fasten a shade or globe 33, (see Fig. 1), to the shade holder. The socket 19, has the usual screw threaded shell portion 33, for holding 30 an incandescent electric light bulb. (Not shown.)

In the form illustrated in Fig. 2, the tubular stem 15^a, extends at right angles to the axial line of the members 18, 24, and may 35 be secured to the wall of a room. A canopy or cover 17, surrounding the stem is provided, as usual. The socket containing members referred to as the combined stem and receptacle, and combined shade holder and 40 locking device, may be constructed in accordance with the one previously described and may contain a socket, having a switch, or without a switch, in which latter case the switch is remotely located. This form of the 45 invention adapts it for use as a wall bracket fixture.

The form illustrated in Fig. 3, the combined stem and receptacle 18^b, and combined shade holder and locking device 24^b, are 50 constructed as before described except that the tubular stem, which is employed in the forms heretofore described, is replaced by a threaded neck 16^b, directly above the receptacle 18^b, which is formed with a flaring 55 part 17^b, that acts as a canopy for covering the wires and connecting members between the fixture and ceiling. The short neck portion 16^b, is formed on the inside of the canopy 17^b and is internally screw threaded, 60 whereby the fixture may be screwed upon a suitable supporting member which is fastened to the ceiling. This form is used where it is desired to have the lamp close to the ceiling.

65 More or less variation of the exact details

of construction is possible without departing from the spirit of this invention; I desire, therefore, not to limit myself to the exact form of the construction shown and described, but intend, in the following claims, 70 to point out all of the invention disclosed herein.

I claim as new and desire to secure by Letters Patent:

1. An electric lighting fixture, comprising 75 a hollow fixture stem formed at one end with means for directly attaching it to a fixture supporting member, and formed at its other end with an open-ended enlargement to provide a receptacle for the reception of the 80 interior of an electric contact member, there being a shoulder formed on the outer face of said enlargement and a lower holding member, at the open end of said receptacle detachably secured against said shoulder and acting to secure said electric contact member in the receptacle, said lower holding member being provided with shade holding means. 85

2. An electric lighting fixture, comprising 90 a hollow fixture stem, formed at one end with a threaded portion for directly attaching it to a fixture supporting member and having an outlet opening adjacent said end, said stem being formed at its other end with an open ended enlargement to provide a receptacle for the reception of the interior of 95 an electric socket, there being an annular shoulder formed on the outer face of said enlargement, and a lower holding member at the open end of said receptacle and detachably secured against said annular shoulder and having an internal shoulder acting to secure said electric socket in the receptacle, said lower holding member being provided with shade holding means. 100

3. An electric lighting fixture, comprising 105 a hollow fixture stem formed at one end with means for directly attaching it to a fixture supporting member and having an outlet opening at said end, said stem being formed 110 at its other end with an open ended enlargement to provide a receptacle for the reception of the interior of an electric socket, and a lower holding member detachably connected to the open end of said receptacle, 115 and having an internal annular shoulder for supporting said electric socket, said lower holding member being provided with shade holding means. 120

4. An electric lighting fixture, comprising 125 a hollow fixture stem formed at one end with means for directly attaching it to a fixture supporting member, and having an outlet opening adjacent said end, said stem being formed at its other end with an open ended enlargement to provide a receptacle for the reception of the interior of an electric socket, there being an annular shoulder formed on the external face of said enlargement, and locking lugs therebelow, and a lower hold- 130

ing member formed with bayonet slots co-
acting with said flange and lugs to detach-
ably connect the enlargement with said
lower holding member, said lower holding
member being also formed with a socket
supporting shoulder and having means for
supporting a shade.

5. In an electric lighting fixture, a tubu-
lar stem formed at one end with a receptacle,
10 having an annular flange on its exterior and
a plurality of lugs therebelow, a lower mem-
ber having a shoulder and bearing against said flange, and a screw
15 threaded in said lower member and protrud-
ing into said notch in the receptacle to pre-
vent relative rotation between said members
and bearing against said flange and said shoulder.

16. Same hereinafter comprising with a tube, a flange

receptacle to prevent relative rotation in one
direction between said members.

6. In an electric lighting fixture, a tubu-
lar stem formed at one end with a receptacle
having an annular flange and lugs therebe-
low, there being a notch in the lower edge of
said receptacle, a lower member formed with
20 bayonet slots for the reception of said lugs
and bearing against said flange, and a screw,
threaded in said lower member and protrud-
ing into said notch in the receptacle to pre-
vent relative rotation between said members
and bearing against said flange and said shoulder.

MAXHEESIOVITZ
